SHORT ROUND CORRECTOR

Lautt Franklin Young, Corpus Christi, Tex.

Application August 3, 1944, Serial No. 547,948

6 Claims. (Cl. 89—33)

(Granted under the act of March 3, 1883, as
amended April 30, 1928; 370 O. G. 757)

1

The invention described herein may be manufactured and used by or for the Government for governmental purposes without the payment to me of any royalty thereon.

The invention relates to machine gun ammunition feeding mechanism, and while applicable to various mechanism, has been here constructed and applied to the feed of present day link belt ammunition into the current Browning machine gun, and particularly the cal. 50 gun used largely in antiaircraft fire. The installations of this gun are largely used in aircraft, as well as in portable or permanent ground units.

The nature of the ammunition, the use of disintegrating metal link belt for making up and holding the rounds, the rapid operation of the feeding and firing mechanism, the limited operating energy available as well as the need for accurate positioning of the cartridges in the loading, firing and ejector mechanism, impose requirements for free interaction of the ammunition and gun parts which it has been found difficult to satisfy, even in the long-developed and extensively used gun named.

Displacement of the bullet too far into the case, which may occur in loading the belt or may occur afterward by collision of the belt with objects, and may readily occur when the neck of the case is not tight enough on the bullet, is the cause of the actual short round, although other faults, including uneven loading of ammunition in the belt, and distorted links are listed under this head.

Where the round itself is actually short, when the belt enters the gun the noses of the normal rounds are guided and held rearwardly by the bunter plate or guide lug at the forward side of the entrance to the feedway, and the rounds are positioned properly for engagement of the extractor in the case groove. The short round, however, will not be so guided by the bunter plate, and is likely to be set too far forward in the feedway for the extractor to engage it properly, and this is one of the principal causes of stoppage under the head of "short round." In such case, the cartridge is not drawn from the belt, no round is loaded, and the operation of the gun ceases after firing of the preceding round. A so-called short round may also cause jamming of the link in the link stripper. There are some twenty more or less common malfunctions of this gun listed under the head of short rounds, but the first two mentioned are the most serious and frequent. The stoppage of such a gun in an encounter is fraught with liability of the most serious conse-

2

quences, among the least of which is failure to overcome an enemy in an encounter, giving him the advantage in offense. Usually stoppage from "short round" during an encounter cannot be remedied in time to enable the gunner to resume attack or defense, and in most cases where the gun is mounted non-flexibly in an airplane, it can only be corrected after grounding of the plane. The import of this in statistics of casualties and losses of matériel has spurred numerous efforts to eliminate malfunction due to short rounds, without a satisfactory remedy heretofore. Altho some of the prior improvements have been of partial benefit, none has warranted adoption as standard manufacture.

The present invention has the avoidance of malfunction due to short rounds as its paramount object, although others of importance are also in view, and have been attained, as will be seen.

Among these is simplicity and low cost of structure, and production and assembly practice. Also, it is sought to avoid need for modification of conventional ammunition and belt forms, or gun structure already in production and in use in very large quantity, and to enable application of the invention to guns already in use at small cost and without return of the gun to arsenals for modification. The latter steps are being successfully carried out extensively, and comparative preliminary tests as well as experience in service use show that the short round difficulty has been eliminated to a great extent by the use of my invention.

Another aim in view is to enable the application of the invention to guns already in use, by men of moderate skill, as mechanics or armorers, and without liability of impairing the safety, mechanical functioning, and ballistic values of the weapons.

An essential requirement for satisfactory performance of the invention is to present means which will function as required for either right or left feed, without change, and without requiring rearrangement or removal for the change of direction of feed.

It is also made unnecessary to remove any parts to afford access to the receiver or loading mechanism parts, or for the manipulation of the cover plate. It is an important purpose to effect positive guidance of the round in the feedway yet leave it comparatively free when at loading position, so that it may have sufficient loose movement to yield downwardly as the extractor rides over the base of the cartridge case, and for free movement in extraction, as well as avoiding

cocking of the round with its butt too high for free passage of the extractor thereover.

One of the most valuable features of the invention is its freedom from liability of impairment by rapid wear, or injury by jamming of belts or rounds due to various causes unrelated to my invention.

I am aware of practices such as shown in the patent to Green, 2,073,632; Turnbull, 2,098,264, and others, all of which are open to serious if not insuperable objections which are obviated by my invention.

It is an important aim of my invention to avoid working upon the projectile in order to effect the necessary corrections, and to present an article which may be readily adapted to a wide range of variation from standard.

Devices functioning by the use of inclined cam faces to engage the tip of the projectile so as to push the cartridge rearwardly are unsatisfactory for several reasons, among which is the fact that the nose of the bullet may be deformed by such a device if the cartridge approaches while much out of line, rendering the course of the projectile erratic on firing. More important is the fact that a frequent cause of short rounds will not be remedied, this being the case where the projectile is set too far back into the cartridge, in which case the base of the round will not extend far enough to the rear to be properly engaged by the extractor even if the nose is accurately guided. Another objection to nose guidance is the tendency to produce a "dum dum" effect by removal of the bullet point and broadening and flattening of the truncated point on impact.

These and other reasons have impelled prior inventors and myself in the devising of means which would operate without engaging the bullet for the purpose of remedying short rounds, but to operate on the cartridge or the links of the belt. As a result the later patent to Green, No. 2,121,794, the Turnbull patent and others including the one to Moore No. 2,327,922, have been issued. The Turnbull device if effective (which experience indicates is unlikely) would remedy only one difficulty which falls under the head of "short round," viz: that where the extractor strikes the butt of the cartridge and drives the case forward, as explained in that patent. It presupposes that the round will be accurately positioned with the end of the cartridge abutting the rear face of the Turnbull anvil block 13, which would be rare in short rounds.

The second Green patent mentioned seeks to effect both the functions of engaging and camming the front edge of the cartridge case rearwardly and also similarly engaging the front edge of the link. This device requires a very complicated structural form in the cam block; it requires a passageway for the bullet which does not permit the loose freedom of movement of the bullet which has been considered desirable; will be difficult to install so as to compensate for variation from standard proportions in gun parts which occur incident to large volume production; it cannot be readily cleared of detritus; it must be made in alternative forms for right and left feed; it is excessively liable to fracture of the delicate thin cam edge and lip at the upper rear side; it limits the clearway between the cover and receiver so that in case of a jammed belt, clearance is made difficult; it is exceedingly liable to malfunction by variation from standard diameters of cartridge neck and metal belt links and

develops excessive retardance of the gun action. All of the foregoing objections have been overcome in my invention, which operates by a camming only on the belt links.

The Moore patent is open to most if not all of the objections pointed out in the Green device, as well as others.

Short round difficulties may be due to slight deformations of links which may occur in the handling of belted ammunition, especially when in long length; and may be due to imperfection of form, especially when a succession of links have similar variances from standard, even if individually within the set tolerances, a cumulative displacement being possible in some cases. The distance between the forward edge of the link and the base of the cartridge will usually not vary materially from standard (3.432 inches) in such cases, and my invention will properly align the round in most distorted links correctly in relation to the extractor within the tolerance for excess permitted in this dimension, as well as variances in width of the links.

The precession of the firing pin action in relation to the bolt movement may in some cases prevent the engagement of the extractor when the round is only very slightly short, and my invention will permit a wide range of advance of firing time and still avoid stoppage from early timing.

Additional objects, advantages and features of invention reside in the construction, arrangement and combination of parts involved in the embodiment of the invention, as will appear or be understood from the following description and accompanying drawings wherein:

Figure 1 is a cross section of a gun in which my invention has been incorporated, the cover being raised;

Figure 2 is a fragmentary enlarged vertical longitudinal section across the cam block and heel of the cover plate;

Figure 3 is a similar view showing the gun barrel;

Figure 4 is a horizontal section through the feedway with the cam in place and cover removed, showing the functioning of my invention with short rounds in course of feeding to the position for extraction from the belt;

Figure 5 is a fragmentary view similar to Fig. 1 showing the cover closed;

Figure 6 is an enlarged top view of the cam block;

Figure 7 is an enlarged rear edge elevation of the block;

Figures 8 to 10 are plan views of respective modifications of the shape of the cam faces of the cam block, and in which a continuous longitudinal key rib is provided;

Figure 11 is a bottom view of a further modification;

Figure 12 is a rear edge view thereof.

Referring to the drawings, there is illustrated a portion of the receiver 20 at the feedway 21 of a gun of the kind before mentioned, with the cover 22 in place. There being no changes whatsoever in the construction or function of the gun action, the mechanism thereof will not be described or shown except as it appears with the essential part of my invention.

It has been customary heretofore to provide a channel or groove 23 transversely across the underside of the thick base or heel portion 24 of the cover, in which a simple bar rectangular in cross section (the "bracket") has heretofore been set,

held by two rivets or screws. This bracket is omitted in my invention, but the groove retained and a hardened steel cam block 25 is provided, having two alined longitudinally extending spaced ribs 26 set snugly in the groove 23 and held by two Allen head screws 27 in the same locations as the screws which formerly held the bracket engaged slidably through the counterbored heel 24 and in tapped holes in the cam block.

This block 25 as actually used is an elongated blank of hardened steel having a thickness in its body part of somewhat less than one quarter inch, a length equal to the width of the cover heel portion 24 and a maximum width from front to back at its middle of approximately five eighths inch.

Its forward edge 29 is rectilinear and parallel to the ribs 26, the latter being spaced from the edge 29 about one eighth inch, and having a width of nearly one quarter inch, and a height from the body of the block not exceeding the depth of the groove so that it may fit in the groove 23 as heretofore formed on the cover in place of the prior bracket.

At the rear face or cam side of the block a central maximum high vertical flat 31 is presented, extending a distance longitudinally of the block somewhat less than half an inch, and from this face right and left vertical planiform link-engaging cam faces or edges 32 and 33 extend to the ends of the block, each with a forward inclination at an angle of approximately ten degrees to the plane of the face 31, the total extent of these cam parts longitudinally of the gun being approximately one quarter inch in the device installed, as heretofore embodied.

Mounted as indicated, when the cover is closed, the face 31 defines the forward limit, or side of the path of the cartridge belt links moving through the feedway, and the lower face 34 of the cam block then lies nearly at the level of the upper sides of the necks of cartridges of the rounds carried by the links so that the angular cam edge 35 formed at the junctions of the cam faces 32 or 33 with the bottom face 34 of the block 25 may engage the extreme forward edges of the passing links and force any rounds which are "short" toward the rear.

The face 34 may be parallel to the top face 30 and subjacent face of the heel of the cover, which is also parallel to the horizontal planiform slightly raised forward or bed face 36 of the bottom of the feedway formed on the receiver. This face 36 constitutes the lower guide surface in the feedway for the necks of the cartridges while moving in the gun to the cartridge stop 37 and link stripper 38 which are located as usual. The forward under face 55 may be relieved, as shown, and slopes upward and forwardly from the face 34.

The top of the receiver in the rear part of the feedway is also formed with the usual lower channel way 39 immediately to the rear of the face 36, extending from left to right, in which the loops of the belt links 40 rest while the rounds are moving through the feedway. This movement of the rounds is effected by the same feed pawl 41 heretofore used in these guns, which is actuated by the same means heretofore familiar in the guns indicated, a holding pawl 42 being located at the lower side of the belt on the gun as before.

In the belted ammunition for these guns, due to the link blanks being stamped rapidly from sheet steel stock and being rapidly processed in

the forming machinery, they will be found to vary considerably in diameter, and this is accentuated by variations from standard thickness of the sheet stock from which link blanks are cut. Also

5 due to peculiar bending forces developed in shaping, or spotty imperfections of quality or thickness of the sheet stock, in the forming process the bends in the loops of the links which receive the rounds therethrough will not be uniformly circular, so that parts are bulged from a symmetrical cylindrical contour while other parts are nearer the case.

However, present link stock affords sufficient edge face for my invention to operate thereon without liability of missing, over-riding, or pressure on the underlying case portion.

This is due to the manner in which my device may be accommodated to the errors in spaces, thicknesses and relative locations of parts, at the feedway and in the belt. As at present

20 manufactured, the forward part of the neck loop 50 of the link is not tightly fitted to the neck 44 of the cartridge case, but has a minimum inside diameter of .560 inch, and assuming a minimum tolerated link thickness of 0.039 inch, and a minimum diameter of the neck of .544, this would give the minimum height of the top of the neck link above the face 36 symmetrically (neck radius .272+link inside radius .280+.039=.591). The neck may be assumed to have a maximum outside diameter of .560 inch.

25 With a maximum clearance of .565 inch between the cam face 34 and lower feedway face 36, there would thus be a minimum working shoulder face at the front of the link above the lower face of the cam of .026 inch, which tests have shown affords more than ample engagement with my cam to effect the proper ordering of the rounds in relation to the loading extractor. As minimum dimensions are exceptional and only occasional and do not

30 exist in a large succession of rounds, there would most of the time be available a more extensive edge or shoulder face of the neck link engaged. In the measurements stated above and herein-after typical extremes of tolerance have been

35 assumed which may or may not be the same as those of actual practice, but will exemplify the possibilities of application of the invention to present guns, and its workability, with current production. Greater tolerances will fall within

40 the margins of safety still remaining as herein disclosed, while other variances from the tolerances stated herein giving greater thickness or greater diameter of the link will be more favorable to my invention.

45 The manner of limiting the neck fit of the loop 50 permits its rear conical part 52 to more readily fit to the shoulder 53 of the case, so that in the loading of ammunition rounds in the belt links the neck loop is not liable to initial expansion as

50 the cartridge neck enters, and the cartridge is very positively stopped in this loop when the case shoulder engages the flared rear part of the link. This makes the space relation between the forward edge of the loop and base of the cartridge case subject to very remote likelihood of objectionable deficiency, and contributes to the dependability of functioning of my invention.

55 As may be seen in Figs. 1 and 4, the rounds feeding into the gun pass between laterally projecting flared forward and rearward guide lugs or bunters 43 on the side plates of the receiver, and the spacing between these lugs is somewhat more than the maximum permissible length of the round, which is 5.45 inches in this particular installation.

When a round moves into the feedway, the neck 44 of the cartridge case 45 will be close to or resting on the forward bed face 36 of the bottom of the feedway, with the bullet 46 clear of the face 36. Assuming that the maximum outside diameter of the neck permitted is .560 inch, the under face 34 of the cam block 25 must clear the feedway bottom at the bed face 36 by at least that distance, but in order to afford some loose movement of the round, and a margin of safety, this clearance is preferably at least .005 inch greater than the maximum possible diameter of the case neck, or .565 inch, in the assumed case.

The limits of tolerance for the positioning of the links on the cartridges are based on the distance between the butt face of the cartridge to the forward edge of the neck loop 50 of the link. The minimum is set at 3.432 inch and the maximum 3.457 inch. With the round in ideal position for engagement of its extractor groove 47 by the bill 48 of the extractor 48 of the loading mechanism, the cam face 31 of my cam block should be at a distance of approximately 3.43 inches forwardly from the base face of the cartridge. This takes advantage of the fact that if the base of the cartridge is as much as one eighth inch—or even more—rearward of the ideal position, the extractor will still function correctly, and so the allowance of excess length between the cartridge base and camming edge of the links is accommodated without special rear guide or stop associated with my invention. By the spacing of my block 25 from the bed face 36 of the feedway as stated, should a cartridge neck of minimum permissible diameter, say .544 inch pass, resting on the bed face 36 and taking into consideration the safety factor of .005 inch over the maximum diameter, there would be a possible maximum clearance between the cam and cartridge neck of .021 inch. Remembering the minimum height involved in the neck link of .591 inch it will be seen that there will be a working shoulder face available at the forward edge of the link of at least .034 inch.

The material of the links is required to be of a hardness of 49, Rockwell C, and it may thus be readily appreciated that the device obtains an ample working face on the link upon which the camming function may be carried out. This also affords a satisfactory margin of safety for variation due to wear and some errors since severe tests have shown that a shoulder face of .018 or less engaged is adequate.

In the application of my invention to use, on account of the possible variation from standard in the distance between the under face 51 of the heel portion of the cover and the bed face 36 of the feedway, it is desirable to complete the manufacture of the receiver and cover before my cam is applied. Variances may occur due to displacement of the bore through the pivot knuckle 54 at the forward end of the cover and in the location of the apertures for the cover pin in the trunnion block 54', as well as variations in shaping, or in finishing the faces of the feedway, and cover parts.

After assembly of the receiver and cover, measurement is made of the spacing between the cover heel face 51 and bed face 36, and my cam block with a shim 28 of proper thickness thereover to leave the proper clearance below is secured in place against the underface of the heel 24 with its ribs 26 in the groove 23.

The shim device may consist of a multiple

layered assembly secured together and secured to the top face 30 removably, each layer being one-thousandth of an inch in thickness. Initially it should be of the maximum thickness which would be required to meet the maximum space tolerance between the heel 24 and the bed face 36 of the feedways, and after a gauge measurement is taken showing the actual space existing when the cover is closed, the number of thousandths of an inch in excess of a minimum desired will indicate the number of layers of the shim which are to be retained, the remainder being removed.

In the preferred embodiment of my invention the under face of the block 25 is formed with a recess 60 extending from the central rear face of the block forwardly to the front edge. In the block of Figures 1 to 6 this recess opens through the central flat 31, and is arcuate, concentric with the axis of a round in loading position against the cartridge stop, and has a radius approximately the same as that of the cartridge neck. The depth of the recess is thus approximately .062 measured from the under face 34 of the block adjacent the angular edge 35.

It will thus be seen that by coordinating my cam with the bed face of the feedway in the gun named and taking advantage of the accommodation to longitudinal variance in one direction of which the gun mechanism is capable, it has been made unnecessary to incorporate many features and elements of construction heretofore used for remedying most of the malfunctions due to short round, and my single simple form of block accomplishes the desired correction and compensations for variations in gun proportions and dimensions, functioning automatically for either right or left hand feed without change or adjustment and without narrowing the clearway objectionably. It is readily accessible in all surfaces for cleaning and inspection and may be quickly renewed in a few moments by the average gunner by removal of fastening screws and replacement.

In the use of my invention, the gun receiver being assembled except that the cam is not in place, a measurement of the space between the face 51 of the heel 24 and the bed face 36 of the feedway is taken. Assuming that the maximum tolerance here has been .771 inch and the minimum .736, the difference of .035 would represent the range of variation which it is necessary to compensate for in the shim 28. Consequently, my cam block could be produced with a body thickness of .171 and on the top face 30 of the block there would be applied the shim 28, shaped in plan to fit the rib and made up of thirty five laminae secured together in a manner familiar in the production of laminated shims, and also secured to the upper face of the cam, but manually detachable singly or in such number as required, by using a knife edge or other tool to lift the corner of the part to be removed, after which the started portion may be peeled off manually. With this arrangement any amount counted in thousandths of an inch by which the clearance between the bed face 36 and heel face 51 falls short of .771 inch will represent the number of laminae which are to be removed. Gages suitably marked to indicate the number of layers to be stripped may be used. The cover being then opened, the cam block with the remaining portion of the shim still secured thereto is set in place and secured with the screws 27 as indicated.

In operation of the gun the ammunition is prepared and fed as usual to the gun from either side, according to the arrangement of the feed

mechanism, without special practice or consideration on account of my invention. As the rounds are drawn in by the feed pawl, normally positioned rounds and links will move without material guidance, but will be held accurately in position longitudinally of the gun by the flat 31 engaging the links, when the round is at the loading position, stopped against the forward cartridge stop 37 and stripper 38, which—like the extractor and other operative parts—will function as heretofore.

In the event that a short round appears and tends to move in a path too far forward, the loop 50 will engage the inclined cam edge 32 or 33, as the case may be, for right or left feed, and the link, with the round carried thereby, will be pressed to the rear in proper operative relation to the extractor and the stripper. Should the cartridge extend to the rear beyond normal, the extractor will ride farther forward thereon but will engage properly on its rearward return movement. The recess 60 will leave the bullet free to move loosely while at this loading position, and particularly vertically so that the heel of the cartridge case may be at a low position to clear the extractor in forward movement, and to yield downward thereto if necessary.

Jams in the feedway sometimes occur which subject the parts therein to severe stresses and shock and it is an advantage of my invention that its parts are practically immune to injury in such manner. The angular edges 35 marking the junction of the lower face 34 with the faces 32 and 33 are preferably of a maximum hardness, so as to minimize wear and denting in case of jams which may force the link edges thereagainst, and under tests these have shown no failures by fracture. They have been found highly effective for the purpose contemplated, in extensive firing tests, with short round defects in the ammunition used.

The form and relation of the cam faces may be considerably varied, as indicated in Figures 8 to 10, the Fig. 9 indicating a continuously curved rear cam edge 55 the central part of which is only slightly arcuate and the ends more pronouncedly curved forwardly. In Fig. 10, the opposite end portions 56 of the rear cam face are extended from the ends of the block diagonally inward and toward the rear with only a slight curvature and are merged in a central curved face portion 57 of much shorter radius.

In Fig. 8 a central flat 58 corresponding to the flat 31 is provided from which respective forwardly curved faces 59 extend to the ends of the block.

The manner of keying the block to the heel 24 may be varied in accordance with any approved practices and other shim forms, or methods of positioning the lower face of the block in relation to the bottom of the feedway may be adopted if found preferable. If closer tolerances in the variations from an ideal clearance between the faces 36 and 51 of the feedway are found possible, an arbitrary medium thickness may be set for my cam block which will function for all dimensions without the use of a shim; or blocks of two different thicknesses might be used respectively for feedway clearances above and below a medial clearance, taking advantage of the possibility of accommodation of my invention to considerable variances in the depth of edge face of the links engaged by my cam block to operate effectively.

It is notable that immaterial camming action occurs between the flat 30 and the links so that

the reduction of the extent of engagement of the flat with the links by reason of the formation of the recess 60, involves small liability of excessive wear or malfunction, it being only necessary to hold the rounds statically at this location after the actual camming has been performed by the edges 35.

As is apparent from the foregoing the presentation of the invention here made, while in detail as to the best form as yet embodied, is purely exemplary and many departures from the specific construction, arrangement and combination of parts, substitution of materials and equivalents mechanical or otherwise may be made without departing from the spirit of the invention presented in the appended claims.

In Figures 11 and 12 there is illustrated a further modification wherein the cam block is of the same conformation in plan as that first described, and similarly adapted to engage the groove in the cover and to be secured. It may have a similarly disposed central flat 61 and right and left cam faces 62 and 63, corresponding to the parts 31, 32 and 33, and a central arcuate recess 64 corresponding to the one 60 before described. The major area of the under face of the block, however, is relieved as at 65 from lines closely parallel to the faces 61, 62 and 63, so that a comparatively narrow bearing face 66 remains, extending from the cam faces forwardly. In practice this face has a dimension of approximately two millimeters at its narrowest part, and is slightly broadened at the outer ends and adjacent the recess 64. This reduces friction on the passing bullets and economizes the power available for the automatic functions of the gun. As a further contribution in this direction the device of Figures 11 and 12 is also bevelled at each end on the under side as at 67 from the level of the relieved face 65 at least, and extending inwardly longitudinally of the block a distance of approximately eight millimeters, although this dimension may be varied as practice shows to be desirable. The relieved face 65 is in the present instance about two millimeters above the face 66, although this measurement may be much less, or more without material effect, a very slight clearance being sufficient, but it is of advantage to make the clearance sufficient to permit a certain degree of rocking of rounds on an axis transverse to the rounds near the cam faces, so that as the ammunition rattles vertically when its direction is abruptly changed at the entrance to the feedway a minimum blocking effect is achieved by avoiding abrupt camming of the rounds upward or downward. The block still closely approximates a rectangle in cross-section in its body portion throughout its length.

In case the depth of relief at 65 is decreased from that shown, the bevels 67 may extend into the relieved surface 65 a distance as far as required to afford the desired function.

Alternatively a single rib 26' may be formed on the top of the cam as in Figs. 8 to 12 extending the full length of the block if need for shims is avoided, and a single rib 26'' may be used, stopping short of the ends of the block, as in Figs. 11 and 12, and the shims slotted to fit therearound.

I claim:

1. A short round corrector for link-belted cased ammunition rounds in machine guns wherein a receiver is included having a transverse feedway provided with a raised forward cartridge-neck-

supporting bottom element and also having an extractor to engage a round positioned midway of the feedway; said corrector comprising a block of a length approximately equal to the width of the receiver of the gun, constructed for fixed attachment to the upper side of the feedway forwardly of the desired path of the belt with the longitudinal axis of the block extending parallel to the feedway bottom for substantial distances from its middle toward each end and having a thickness sufficient to space its under side from the raised forward lower surface of the feedway a distance equal to the diameter of a case neck of a passing round plus maximum tolerance in corresponding measurement of round elements, the inclusive clearance being less than the thickness of belt link edges, said block having a rear face on each end portion inclined from without said path adjacent the ends of the block rearwardly to the rearward limit for position of the belt, said block stopping at said limit, an arcuate recess formed in the under face of the block nearly concentric with the axis of a round normally positioned for engagement by said extractor for loading, whereby to clear a cartridge neck slightly, the rearmost inner parts of said rear faces stopping adjacent the sides of said recess, said block having a flat at its rear side above said recess parallel to said path and adapted to form a stop for a cartridge case edge.

2. In combination with a machine gun having a receiver with an ammunition feed passage through which an ammunition belt may operatively pass from either side of the gun, a guide element having a rearwardly presented arcuate margin curved symmetrically from its center to each side of the receiver for engagement with the belt fed from either side of the gun to shift the belt and ammunition carried thereby rearwardly with respect to the receiver.

3. The combination with a machine gun having a receiver, there being a transverse feed channel in said receiver through which a cartridge belt of the metallic link disintegrating type is fed in firing the gun, of a guide element secured within said channel transversely of the gun, said element having a rearward guide edge generally parallel with the direction of movement of the belt therethrough, said edge comprising a rear-

ward central portion and forwardly sloping side portions, all said portions merging into a continuous guide edge, and means removably securing said element to the receiver within the feed channel in such position that said guide edge engages and limits the forward edges of each belt link as it is moved into cartridge-extracting position to thereby limit the forwardmost position of the cartridge therein.

4. The combination with a machine gun provided with a receiver having a feed channel therethrough transversely of the gun and into which a cartridge belt of the metallic link disintegrating type is fed in firing the gun, of a guide plate secured within said channel at the top thereof, said plate having its rearward edge shaped to provide a transversely-extending continuous guide edge having a central portion terminating in forwardly-inclined end portions, said guide edge being constructed and arranged to engage the forward top edge portion of each successive link as it is moved into cartridge-extracting position in said feed channel, to thereby limit the forwardmost position of its cartridge when in position to be extracted from the belt.

5. The combination recited in claim 4, said receiver including a top cover, means rigidly securing said plate to the under side of said cover, and a shim interposed and clamped between said plate and cover.

6. The combination recited in claim 4, said receiver including a top cover having a transverse groove in its under side, said plate having a rib fitting said groove, screw means passing through said cover into said plate to rigidly attach said plate to said cover, and a shim clamped between said plate and cover.
